CLAIM

The ornamental design for a covered mixing bowl or the like, as shown and described.

DESCRIPTION

FIG. 1 is a top perspective view of the covered mixing bowl or the like showing my new design; FIG. 2 is a top plan view thereof; FIG. 3 is a side elevational view thereof; FIG. 4 is a front elevational view thereof; FIG. 5 is an end elevational view thereof; FIG. 6 is a bottom plan view thereof; and FIG. 7 is an exploded top perspective view thereof. The bottom interior of the mixing bowl and the underside of the cover are conventional in appearance.
